UNITED STATES PATENT OFFICE.

JOSEPH TABARA, OF WOODHAVEN, NEW YORK.

DESIGN FOR A TOY.

55,083.

Specification for Design.

Patented May 4, 1920.

Application filed October 15, 1919. Serial No. 330,919. Term of patent 3½ years.

To all whom it may concern:

Be it known that I, JOSEPH TABARA, a citizen of Poland, and a resident of Woodhaven, in the county of Queens and State of New York, have invented a new, original, and ornamental Design for a Toy, of which the following is a specification, reference being had to the accompanying drawings, forming part thereof.

The figure is a front view of a toy showing my new design.

I claim—

The ornamental design for a toy as shown.

JOSEPH TABARA.
